MIXING DEVICE

Rudolph Guth, Cleveland, Ohio

Application January 9, 1931. Serial No. 507,713

9 Claims. (Cl. 299—84)

This invention relates to an improved form of mixing device and relates to the same general subject matter as disclosed in my pending application, Serial No. 420,570, filed January 13, 1930.

Although the present device is intended especially for the mixing of soap and water into suds for use in connection with the cleaning of automobiles, etc., yet it is to be understood that the invention as herein set forth comprehends any and all uses to which this form of structure may be put, as for instance in the mixing of other materials.

In the use of devices of this same general nature, it has been found that in some localities, the pressure of the water in the municipal supply system is so great that it is not well adapted for direct application to a body of soap. Such excess pressure of the water as it impinges upon the body of soap or other material within the container, causes too rapid consumption of the same and an improper combination of the soap and water for the consistency of mixture.

It is therefore the object of the present invention to devise an adjustable means for relieving the pressure of the water supply so as to reduce the force of the same as it impinges upon the soap and thereby obtain the proper dissolving action of the water upon the soap as well as the proper consistency of mixture.

Other objects will appear from the following description and claims when considered together with the accompanying drawing.

Fig. 1 is a plan view of my present improved form of device; and Fig. 2 is a sectional view taken on line 2—2 of Fig. 1.

It is to be understood that the present disclosure is merely for purposes of illustration and that there may be devised various modifications without departing from the spirit of the present invention as herein set forth and claimed.

The container 1 is provided with the false bottom 2 so as to provide a mixing chamber 3 beneath the same. The bottom 2 is provided with a centrally disposed opening, and the vertically arranged perforated tube 4 is connected to the opening so as to afford communication through the tube 4 and into the chamber 3. The tube 4 may extend throughout the entire height of the container 1, that is, so as to engage the under side of the top thereof or may terminate a short distance below the same.

In the present form of structure, the upper end of the tube 4 is shown as receiving the central depending portion of the top 5. This top is secured to the body 1 of the container in the usual manner, and there is attached thereto by means of the bolts 6 the removable central portion 7 which has the centrally disposed chamber 7a below the same. Around the lower outer edge of the wall of chamber 7a, there are provided a se-

ries of spaced, annularly disposed openings 8 which permit passage of water or other fluid outwardly therethrough into the space between the body 1 of the container and the tubular member 4. This space is occupied by soap of proper consistency which is dissolved by the water and carried through the openings of tube 4.

The central part 7 of the top has an upwardly extending screw-threaded projection 9 to which may be attached a valve casing 10 for supplying water to the chamber 7a. The valve casing 10 is of tubular form so as to permit passage of water or other fluid therethrough and has its upper end screw-threaded at 10a for attachment of a hose or other means of connection from the source of water supply.

The apertured web portion 10b provides a seat for the valve 11 which normally occupies closed position therewith by virtue of the coil spring 12 surrounding the valve stem. This valve may be opened, however, by turning the handle 13 about the axis of the valve stem and while maintained in such position, there will be permitted a flow of water or other fluid through the tubular casing 10, into the chamber 7a and thence through the openings 8 into the compartment occupied by the soap. Upon release of handle 13 and closing of the valve, the mixing operation as well as the discharge of suds from the mixing chamber will cease.

Any fluid which might then drain from the upper part of the device will be held within the mixing chamber. The particular type of valve herein disclosed is old and well known and does not enter the present invention, except insofar as it serves as a means for opening and closing the passage through the tubular casing 10.

Any other suitable form of valve may be employed for this same purpose and in this same combination.

Through the center of the bottom wall of chamber 7a, there is an aperture over the lower side of which is applied the casting 14. This casting has a tapering bottom which is provided with an opening therethrough.

This casting is provided also with a transverse web portion 14a in which is mounted an adjustable screw plug closure 15 which has its lower end tapered for engagement in the tapered edge of the opening in the bottom of the casting 14. This casting is screwed to the under side of the wall 7a, as indicated in the drawing. The upper end of the screw plug 15 is provided with a slot 15a for engagement by a screw driver for adjusting the plug to the desired position so as to vary the degree of fluid which is permitted to pass through the opening in the bottom of the casting 14.

In this way, the pressure through the holes 8 can be more or less relieved and the water which is permitted to pass through the opening in the casting 14 will pass directly into and through the tube 4 and thence into the mixing

chamber 3 where the suds are formed by the churning action which there takes place. As illustrated in Fig. 2, the upper end of the tube 4 engages about the central depending flange 5 portion provided about the opening through the bottom of chamber 7a.

In actual practice, when the present form of device is adopted for use in a given locality, the screw plug 15 will be set so as to relieve to the proper degree any excess pressure in the water supply line and thereby obtain the proper degree of pressure through the openings 8. Access may be readily had to the upper end of the screw plug 15 when the valve casing 10 is removed from the top of the container. This device is then in condition for continued use in spite of the excessive degree of pressure in the main supply line. If the pressure in any given supply line should warrant, the plug may be closed entirely, so that the present form of device is capable of universal application in all communities.

The goose-neck 16 is provided in the side wall of the mixing chamber 3 for discharge of the mixture of soap and water or other ingredients therethrough. This goose-neck will be of substantially the same form herein disclosed and will be attached at approximately the same point with respect to the depth of the mixing chamber 3, as indicated in Fig. 2 of the drawing. The screw plug 17 closes an opening through the wall 1 just above the false bottom 2, and upon removal of this plug, it is possible to ascertain the necessity of replenishing the supply of soap within the container.

Thus, I have devised an apparatus with means of adjustment whereby the proper degree of pressure may be supplied to the body of soap within the container and any excess pressure of the main line relieved. In this way, there may be obtained the proper dissolving action of the water upon the soap, while the water which is permitted to flow directly through the tube 4 will serve to mix with the soap solution in the chamber 3 so as to form the proper degree of consistency in the mixture. Thus, there is obtained a proper balance between the water which passes directly through the tube 4 and the mixture of soap and water produced by the dissolving action of the water which is permitted to pass through the openings 8. The result is that there is obtained in the mixing chamber 3, the desired consistency of suds and at the same time, the dissolving action is produced in a most efficient manner, in spite of the prevailing excessive pressure in the water supply line.

The present form of device is not only efficient in its operation but is comparatively simple in structure.

What I claim is:

1. A mixing device comprising a container having a central opening in the otherwise imperforate bottom thereof, a centrally disposed perforated tubular member spaced from the wall of said container so as to afford an intermediate space for material to be formed into a mixture, said tubular member communicating with said bottom opening, a cover for said container, a centrally disposed adjustable opening through said cover and adapted for the introduction of plain liquid directly through said tubular member, said cover having an annular series of openings therethrough adapted to provide a spray of liquid directly upon the material within the container the adjustment of said central opening being independent of said annularly disposed openings,

and means for supplying liquid to said adjustable opening and to said annular openings, whereby the material may be dissolved by the liquid and discharged through said tubular member to said bottom opening, and a variable quantity of plain liquid may be passed directly through said tubular member and discharged with the dissolved material through said bottom opening.

2. A mixing device comprising a container having a bottom discharge opening, a tubular perforated member spaced from the wall of said container so as to afford an intermediate space for solid material to be dissolved, said tubular member communicating with said discharge opening and affording the only passage through the container bottom, a cover for said container, said cover having a central opening therethrough in registry with the upper end of said tubular member for the introduction of plain liquid directly through said tubular member, means for adjusting the size of said opening, said cover having also an annular series of openings therethrough and being adapted to provide a spray of liquid directly upon the material within said container, and a single means for supplying a liquid to said central opening and to said annular openings, whereby the material may be dissolved by the liquid and discharged through said tubular member to said bottom opening, and a variable quantity of plain liquid may be passed directly through said tubular member and discharged with the dissolved material through said bottom opening.

3. A mixing device comprising a container having a bottom discharge opening, a tubular perforated member spaced from the wall of said container so as to afford an intermediate space for solid material to be dissolved, said tubular member communicating with said discharge opening and affording the only passage through the container bottom, a cover for said container, said cover having a central opening therethrough in registry with the upper end of said tubular member for the introduction of plain liquid directly through said tubular member, said cover having also an annular series of openings therethrough and being adapted to provide a spray of liquid directly upon the material within said container, a single means for supplying a liquid to said central opening and to said annular openings, and separate means for varying the quantity of liquid through said central opening, whereby the material may be dissolved by the liquid and discharged through said tubular member to said bottom opening, and a variable quantity of plain liquid may be passed directly through said tubular member and discharged with the dissolved material through said bottom opening.

4. A mixing device comprising a container having a bottom discharge opening, a tubular perforated member spaced from the wall of said container so as to afford an intermediate space for solid material to be dissolved, said tubular member communicating with said discharge opening and affording the only passage through the container bottom, a cover for said container, said cover having a central opening therethrough in registry with the upper end of said tubular member for the introduction of plain liquid directly through said tubular member, said cover having also an annular series of openings therethrough and being adapted to provide a spray of liquid directly upon the material within said container, a single means for supplying a liquid to said central opening and to said annular openings, means for normally closing said liquid-supplying means,

- and separate means for varying the quantity of liquid through said central opening, whereby the material may be dissolved by the liquid and discharged through said tubular member to said bottom opening, and a variable quantity of plain liquid may be passed directly through said tubular member and discharged with the dissolved material through said bottom opening.
5. A mixing device comprising a container having a bottom discharge opening, a tubular perforated member spaced from the wall of said container so as to afford an intermediate space for solid material to be dissolved, said tubular member communicating with said discharge opening and affording the only passage through the container bottom, a cover for said container, said cover having a central opening therethrough in registry with the upper end of said tubular member, said cover having also an annular series of openings therethrough and being adapted to provide a spray of liquid directly upon the material within said container, said cover having a centrally disposed liquid chamber with said annular openings in the outer edge portion and surrounding said central opening, the central portion of said chamber having a downwardly extending portion with the said central opening in the bottom thereof and being adapted for delivery of plain liquid directly into the upper end of said tubular member, a normally closed spring valve for controlling the supply of liquid to said chamber for passage through said central opening and through said annular series of openings, and separate and independently adjustable means for varying the quantity of liquid through said central opening, whereby the material may be dissolved by the liquid and discharged through said tubular member to said bottom opening, and a variable quantity of plain liquid may be passed directly through said tubular member and discharged with the dissolved material through said bottom opening.
6. A mixing device comprising a container having a central opening in the otherwise imperforate bottom thereof, a centrally disposed perforated tubular member spaced from the wall of said container so as to afford an intermediate space for material to be formed into a mixture, said tubular member communicating with said bottom opening, a cover for said container, said cover having a plurality of openings located above said intermediate space for the supply of liquid directly to the material therein, a liquid supply connection on said cover for said openings, a one-way valve on said cover for controlling the flow of liquid through said supply connection to said openings, and adjustable means on said cover capable of independent manipulation for relieving the pressure of liquid through said openings by transmitting a portion thereof directly through said tubular member said adjustable means being located in registry with said tubular member, whereby this device may be connected to various water supply lines and the pressure thereof relieved to the necessary degree in order to obtain proper dissolving action thereof upon the material within the container.
7. A mixing device comprising a container having a central opening in the otherwise imperforate bottom thereof, a centrally disposed perforated tubular member spaced from the wall of said container so as to afford an intermediate space for material to be formed into a mixture, said tubular member communicating with said bottom opening, a cover for said container, said cover having a plurality of openings located above said intermediate space for supply of liquid to the material therein, a liquid supply connection on said cover for said openings, a normally closed, spring-controlled, one-way valve on said cover for controlling the flow of liquid through said supply connection to said openings, said cover having a central opening in the direct path between said supply connection and said tubular member, and an adjustable means for varying the capacity of said opening independently of said one-way valve, whereby the supply connection may be attached to various water supply lines and the pressure thereof relieved to the necessary degree in order to obtain proper dissolving action thereof upon the material within the container, and access may be had to said adjustable means upon removal of said liquid supply connection.
8. A mixing device comprising a container having a separate chamber therebeneath, said container having a central opening providing communication between the otherwise imperforate bottom thereof and said chamber, a centrally disposed perforated tubular member spaced from the wall of the container so as to afford an intermediate space for material to be formed into a mixture, said tubular member communicating with said central opening, means at the top of said container for introducing liquid directly to the material in said intermediate space so as to dissolve the same and directly to the upper end of said tubular member, whereby the material may be dissolved and discharged through said tubular member into said chamber, and plain liquid may be supplied directly through said tubular member to said chamber, and a goose neck outlet member for said chamber with the bent portion thereof extending above its point of connection therewith.
9. A mixing device comprising a container having a central opening in the otherwise imperforate bottom thereof, a centrally disposed perforated tubular member spaced from the wall of said container so as to afford an intermediate space for material to be formed into a mixture, said tubular member communicating with said bottom opening, a cover for said container, said cover having a plurality of openings located above said intermediate space for supply of liquid directly to the material therein, a detachable liquid supply connection on said cover for said openings, a normally closed, spring-controlled, one-way valve on said cover for controlling the flow of liquid through said supply connection to said openings, said cover having a central opening in the direct path between said supply connection and said tubular member, and an adjustable means for varying the capacity of said opening independently of said one-way valve, whereby the supply connection may be attached to various water supply lines and the pressure thereof relieved to the necessary degree in order to obtain proper dissolving action thereof upon the material within the container, and access may be had to said adjustable means upon removal of said liquid supply connection.

RUDOLPH GUTH. 145
